ART OF CRACKING OILS.

Application filed April 1, 1927. Serial No. 180,149.

This invention relates to improvements in the cracking of heavier hydrocarbon oils, such as gas oil or kerosene, in order to produce therefrom lighter hydrocarbon oils, such as gasoline or pressure distillate. The invention relates particularly to improvements in cracking operations carried out in externally heated, single pass, tubular oil cracking stills. In referring to single pass cracking operations, reference is made to cracking operations in which the oil supplied is circulated but once through the oil heating tubes of the still. The invention includes operations in which vaporized fractions are refluxed and recirculated through the oil heating tubes, but it is to be distinguished from operations in which the fresh oil itself or any unvaporized portion thereof is recirculated through the heating tubes. 20 This application is in part a continuation of my prior application filed August 28, 1922, Serial No. 584,711.

The invention provides an improved method of cracking different grades of hydrocarbon oils in which each grade of oil is treated under conditions most advantageous for the cracking of that particular grade of oil and in which the several operations are combined in such a manner that a greater yield, better quality of product and more efficient operation may be obtained than it is possible to secure by the separate treatment of the individual grades of oil or a similar treatment of the oil mixture.

35 In its broader aspect the present invention provides an improved method of cracking hydrocarbon oils in which the oil is heated to the cracking temperature in a single pass cracking coil and the hot products therefrom discharged into a body of oil maintained at the cracking temperature and in which additional oil, preheated by indirect heat exchange with the vapors generated during the cracking operation, is introduced 40 directly into the liquid body, only reflux condensate free from unvaporized constituents which have been previously subjected to the cracking temperature being permitted to pass through the single pass cracking coil in admixture with the fresh oil supplied thereto.

The process of the invention is particularly advantageous in connection with the

simultaneous treatment of relatively heavy hydrocarbon oils, such as gas oil or fuel oil, and of lighter and more refractory oils, such as kerosene or rerun pressure distillate bottoms.

In the cracking of the more refractory hydrocarbon oils, for example, kerosene or very light gas oils, it is advantageous to use a higher temperature to produce the desired cracking reaction, say to produce gasoline, than is commonly used in the treatment of heavier oils, and treatment of the heavier grades of hydrocarbon oils at the temperatures required to crack the more refractory constituents of lighter grades within commercially practicable periods of time results in the formation of excessive quantities of fixed gases and carbon or coke.

In the combined treatment of different grades of oil according to the present invention, a body of the heavier oil is maintained at a temperature advantageous for cracking its constituents while the more refractory lighter oil is heated to an advantageous cracking temperature in a single pass heating coil and the hot products discharged therefrom into the body of heavier oil. The heat required to maintain the body of heavier oil at the cracking temperature may be supplied entirely by the heat in the high temperature products introduced thereto from the single pass heating coil or this heat may be supplemented by the application of external heat.

At the higher temperatures employed in cracking the more refractory oils it is essential for safety and efficiency of operation to protect the heating tubes against overheating and the formation of carbon deposits therein and at the same time to maintain a high average temperature differential between the heating gases and the heat transferring surfaces. In the operation of the present invention the deposition of carbon in the heating tubes is avoided by circulating therethrough only the more refractory oils which do not cause excessive carbon formation at the temperatures employed and avoiding the recirculation of unvaporized oil which has been once subjected to cracking conditions and which accordingly contains, in solution and in suspension, pitch-like constituents, while a high average tem-

perature differential between the heating gases and the heat transferring surfaces is maintained and excessive local overheating avoided by recirculating a portion of the heating gases which have passed over the heating tubes countercurrent to the flow of oil therethrough and admixing them with the hot products of combustion from the firebox to temper the latter prior to their contact with the oil containing tubes. By recirculating a portion of the heating gases the volume and accordingly the velocity of the heated gases contacting with the heating tubes is increased. The increased velocity promotes an increase in the rate, and a more uniform distribution, of the heat absorption throughout the bank of heating tubes. Thus, the extremely high temperatures necessary for most efficient combustion of the fuel used may be permitted without subjecting the oil containing tubes to contact with heating gases at excessive temperatures while at the same time a large portion of the heat contained in the products of combustion is efficiently transmitted to the oil being treated.

The higher temperature used to crack the lighter and more refractory hydrocarbon oil tends to promote the formation of fixed gases and unstable, unsaturated compounds, the presence of which are objectionable in the finished product. In the operation of the present invention, however, in which the lighter oils are separately heated to their cracking temperature and subsequently introduced into a body of heavier oil maintained at the cracking temperature, the unsaturated constituents formed in the first operation apparently tend to react with constituents of the body of hot heavier oil to form more saturated compounds. An increased yield of constituents suitable as components of the desired gasoline or pressure distillate is obtained and the formation of fixed gases and unstable, unsaturated compounds reduced.

Where the additional fresh oil supplied to the body of heavy oil is preheated to substantially the temperature of the liquid body before its introduction thereinto the amount of heat required to be supplied externally to the liquid body in order to maintain it at the cracking temperature is materially reduced and in some cases the application of external heat to the reservoir may be dispensed with entirely, thereby avoiding any danger incident to the formation of heat insulating carbon deposits on the heated surfaces of the reservoir.

The additional fresh heavy oil introduced to the reservoir may advantageously be passed in countercurrent flow and in indirect heat exchanging relation with the vapors generated in the cracking operation before the latter are permitted to cool appreciably.

The fresh oil may thus be preheated to a temperature approaching the temperature of the liquid body to which it is introduced and the vapors refluxed by the cooling effect of the fresh oil. The vapors remaining uncondensed may advantageously be subjected to a further refluxing operation in direct contact with a fresh lighter oil and this further refluxing operation controlled by regulating the introduction of the fresh lighter oil thereto so that the desired gasoline product or pressure distillate may be directly produced without subsequent re-distillation. The reflux condensates from both refluxing operations together with the fresh lighter oil introduced to the latter refluxing operation may be returned directly to the single pass heating conduit and additional lighter oil may be independently supplied therewith as desired. It will be noted, however, that neither the heavier oil itself nor any of its unvaporized constituents are permitted to pass through the heating conduit with the more refractory constituents.

The invention will be further described in connection with the accompanying drawings which illustrate, in a diagrammatic and conventional manner in elevation and partly in section, an apparatus adapted for the practice of the process of the invention, but it is intended and will be understood that this further description and illustration are for the purpose of exemplification, but the invention is not limited thereto.

In the drawings:

A single-pass externally heated, tubular cracking still is shown discharging into a shell still or reservoir from which the vapors of the cracked oil are taken off. The single-pass cracking still or heater comprises a furnace 1 in which a battery of heating tubes 2 are arranged. Oil is forced through the heating tubes by means of a pump 3, entering the heating tubes through connection 4 and, after passing once therethrough, being discharged through connection 5. The heating furnace 1 is provided with a firebox 6 and a stack flue 7, heating gases being circulated from the firebox through the heating furnace over the oil-containing heating tubes therein to the stack flue. The firebox 6 is provided with means for burning the fuel employed to supply the heat used in the cracking operation. A burner for gaseous or liquid fuel is shown at 8. Before the hot products of combustion in the firebox 6 come in contact with the oil heating tubes 2 in the furnace 1, they are admixed with a part of the heating gases which have passed over the oil heating tubes and which are returned through connection 9. The connection 9 is provided with an inlet 10 adjacent the exit to the stack flue from the furnace and with an outlet 11 through

which the heating gases withdrawn from near the outlet of the furnace are returned and admixed with the hot products of combustion. The return connection 9 includes a 5 blower 12 which may be operated by a steam jet 13 or other suitable means for maintaining circulation of the returned heating gases.

The oil forced through the heating tubes 10 2 includes fresh oil and constituents refluxed from vapors of the cracked oil discharged from the single pass cracking still or heater. In the apparatus illustrated fresh oil, of a lighter character, is supplied from a receptacle 14 through connection 15, and constituents refluxed from the vapors of the cracked oil in the reflux towers 21 and 22 together with additional fresh oil introduced to the tower 22 from receptacle 33 by the pump 35 20 are collected in the receptacle 16 and supplied therefrom through connection 17 to the pump 3 and forced thereby, together with any fresh oil from the receptacle 14, through the heating tubes 2. The reflux receptacle 16 may be insulated, and the reflux 25 may be returned to the heating tubes at a more or less elevated temperature. The oil discharged from the single-pass cracking still or heater through connection 5 is introduced into the reservoir 18 through pipe 19. Vapors from reservoir 18 escape through connection 20 to the reflux towers 21 and 22. Uncondensed vapors escaping from reflux 30 tower 22 through connection 23 are discharged to a condenser (not shown) in which the vapors of the cracked oil, forming the desired distillate, are condensed. Pressure in the cracking system may be maintained and regulated by valve 24 arranged between the 35 reservoir and reflux towers, or by valve 25 arranged between the reflux towers and the condenser, or by suitable valves arranged beyond the condenser. Fresh oil, of a heavier character, is independently supplied from receptacle 27 to the pump 34 and forced 40 thereby into the body of oil in the reservoir 18 through the reflux tower 21, in indirect heat exchanging relation with the hot vapors therein, by means of the connection 28 and pipe 29. Valved connection 30 provides a by-pass for the fresh oil around the reflux 45 tower 21. A connection 26 is shown for withdrawing tar and fluid residues from the reservoir 18. The unvaporized residue of the oil discharged into the reservoir from the 50 single pass tubular cracking still or heater and of the fresh heavier oil independently introduced thereto may be withdrawn through this connection. During periods 55 when fresh oil is not introduced into the reservoir, as at the beginning or end of a run, the reflux tower 21 may be cooled by oil circulated from the receptacle 27 through the reflux tower and discharged through 60 connection 31, or additional cooling oil may

be so supplied and a part of this oil introduced into the reservoir. The reservoir 18 may be heated by means of a furnace 32 in addition to the heat supplied internally by the hot products discharged from the 70 single-pass heater, or it may be heated internally only by the hot products discharged from the single-pass heater. The reservoir, particularly where it is heated internally only, by the hot products discharged from 75 the single-pass heater, and the connection between the single-pass heater and the reservoir may with advantage be insulated to prevent heat loss.

As an example of one particularly advantageous method of operation of the apparatus illustrated in the drawings, in the combined treatment of a heavy gas oil, a light gas oil and a kerosene character distillate, according to the invention, the lightest or 80 kerosene character distillate may be supplied from the receptacle 14 directly to the single-pass heating conduit 2 where it is heated to a temperature of from about 800 to 1200 degrees F. The heavy gas oil may be supplied from the receptacle 27 by the pump 34 to the heat exchanger or reflux tower 21 and from thence to the reservoir 18 through connection 28 and pipe 29. The light gas oil may be supplied from the receptacle 33 by pump 85 35 to the reflux tower 22. The body of oil in the reservoir 18 may advantageously be maintained at a temperature of 700 to 850 degrees F. The vapors liberated in the reservoir 18 pass successively through the reflux 90 towers 21 and 22. The vapors in the reflux tower 22 may be subjected to a refluxing operation in direct contact with the light gas oil introduced thereto from receptacle 33 and the light gas oil preheated thereby. 100 The head temperature of the tower 22 may be regulated by the amount of fresh oil supplied thereto, to produce a distillate having the desired end point. All of the lightest or kerosene character distillate may thus be 105 required to pass through the single pass heating conduit where it is subjected to the highest temperatures, and vaporization and escape of the lighter uncracked constituents thereof without being subjected to the cracking 110 conditions prevented.

It is apparent that various modifications of the process embodying the invention may be made, for example, in the combined treatment of two grades of oil, the heavier oil 115 may be supplied from the container 27 to the reservoir 18 while the lighter oil may be introduced entirely through the reflux tower 22 from the receptacle 33 or directly introduced into the heating conduit 2 from the receptacle 14. When possible, however, it is 120 advantageous to regulate the refluxing operation as desired by the introduction of a portion of the lighter oil to the reflux tower 22 and to introduce any excess of the lighter 125 oil 130

oil, above that required to produce the desired refluxing action, directly into the heating conduit.

I claim:

- 5 1. An improved process for cracking hydrocarbon oils comprising passing a stream of oil once through a heating conduit and heating it to a cracking temperature therein, discharging the hot products from the heating conduit directly into a body of oil maintained in a reservoir at a cracking temperature, passing an additional supply of fresh oil through a reflux condenser in indirect heat exchanging relation with the vapors generated in the cracking operation to preheat the fresh oil and condense the heavy insufficiently cracked vapors and introducing the fresh oil so preheated directly into the body of oil in the reservoir, subjecting the uncondensed vapors from the first refluxing operation to a further refluxing operation in direct contact with fresh oil, returning the condensate from both refluxing operations together with unvaporized fresh oil from said further refluxing operation to the heating conduit, and drawing off unvaporized residual oil from the reservoir.

10 2. An improved process for cracking hydrocarbon oils comprising passing a stream of oil once through a heating conduit and heating it to a cracking temperature therein, discharging the hot products from the heating conduit directly into a body of oil maintained in a reservoir at a cracking temperature, passing an additional supply of fresh oil through a reflux condenser in indirect heat exchanging relation with the vapors generated in the cracking operation to preheat the fresh oil and condense the heavy insufficiently cracked vapors and introducing the fresh oil so preheated directly into the body of oil in the reservoir, subjecting the uncondensed vapors from the first refluxing operation to a further refluxing operation in direct contact with fresh oil, introducing the condensate from both refluxing operations together with unvaporized constituents of the fresh oil introduced to said further refluxing operation and an additional quantity of fresh oil independently supplied to the heating conduit, and drawing off unvaporized residual oil from the reservoir.

15 3. In the cracking of hydrocarbon oils, the improvement comprising passing a stream of light oil once through a heating conduit and heating it to a cracking temperature therein, discharging the hot products from the heating conduit directly into a body of heavy oil maintained in a reservoir at a cracking temperature, passing fresh heavy oil through a reflux condenser in indirect heat exchanging relation with the vapors generated in the cracking operation to preheat the fresh heavy oil and condense the heavy insufficiently cracked vapors, introducing the heavy oil so preheated directly into the body of hot oil in the reservoir, subjecting remaining uncondensed vapors to a further refluxing operation in direct contact with fresh light oil, returning reflux condensate from both refluxing operations together with the fresh light oil introduced to said further refluxing operation, to the heating conduit, and independently introducing an additional quantity of fresh oil lighter than that supplied to said further refluxing operation to the heating conduit.

20 4. In the cracking of hydrocarbon oils, the improvement comprising passing a stream of light oil once through a heating conduit and heating it to a cracking temperature therein, discharging the hot products from the heating conduit directly into a body of heavy oil maintained in a reservoir at a cracking temperature, passing fresh heavy oil through a reflux condenser in indirect heat exchanging relation with the vapors generated in the cracking operation to preheat the fresh heavy oil and condense the heavy insufficiently cracked vapors, introducing the heavy oil so preheated directly into the body of heavy oil in said reservoir, subjecting the remaining uncondensed vapors to a further refluxing operation in direct contact with fresh light oil, introducing to the heating conduit the condensate from both refluxing operations, together with the unvaporized portion of the fresh light oil introduced to said further refluxing operation and an additional quantity of fresh light oil independently supplied.

25 5. In the cracking of hydrocarbon oils, the improvement comprising passing a stream of light oil once through a heating conduit and heating it to a cracking temperature therein, discharging the hot products from the heating conduit directly into a body of heavy oil maintained in a reservoir at a cracking temperature, passing fresh heavy oil through a reflux condenser in indirect heat exchanging relation with vapors generated in the cracking operation to preheat the fresh heavy oil and condense the heavy insufficiently cracked vapors, introducing the heavy oil so preheated directly into the body of hot oil in the reservoir, subjecting remaining uncondensed vapors to a further refluxing operation in direct contact with fresh light oil, returning reflux condensate from both refluxing operations together with the fresh light oil introduced to said further refluxing operation, to the heating conduit, and independently introducing an additional quantity of fresh oil lighter than that supplied to said further refluxing operation to the heating conduit.

30 6. An improved process for cracking hydrocarbon oils comprising passing a stream of oil once through a heating conduit and heating it to a cracking temperature therein, discharging the hot products from the heating conduit directly into a body of heavy oil maintained in a reservoir at a cracking temperature, passing fresh heavy oil through a reflux condenser in indirect heat exchanging relation with the vapors generated in the cracking operation to preheat the fresh heavy oil and condense the heavy insufficiently cracked vapors, introducing the heavy oil so preheated directly into the body of heavy oil in said reservoir, subjecting the remaining uncondensed vapors to a further refluxing operation in direct contact with fresh light oil, returning reflux condensate from both refluxing operations together with the fresh light oil introduced to said further refluxing operation, to the heating conduit, and independently introducing an additional quantity of fresh oil lighter than that supplied to said further refluxing operation to the heating conduit.

the heating conduit directly into a body of oil maintained in a reservoir at a cracking temperature, passing an additional supply of fresh oil through a reflux condenser in indirect heat exchanging relation with the vapors generated in the cracking operation to preheat the fresh oil and condense the heavy insufficiently cracked vapors and introducing the fresh oil so preheated directly into the body of oil in the reservoir, sub-

jecting the uncondensed vapors from the first refluxing operation to a further refluxing operation by heat exchange with fresh oil and returning the condensate from both refluxing operations together with fresh oil 15 preheated in said further refluxing operation to the heating conduit.

In witness whereof, I have subscribed my name.

EDWARD W. ISOM.
